UNITED STATES PATENT OFFICE.

JOHN CRAWLEY, OF PERRYSVILLE, INDIANA.

IMPROVEMENT IN GOVERNOR STOP-VALVES.

Specification forming part of Letters Patent No. **56,186**, dated July 10, 1866.

To all whom it may concern:

Be it known that I, JOHN CRAWLEY, of Perrysville, in the county of Vermillion, State of Indiana, have invented a new and Improved Governor and Stop Valve; and I do hereby declare that the following is a full, clear, and exact description thereof, which will enable others skilled in the art to make and use the same.

This invention relates to new and useful improvements in governor-valves of that class which are available also as stop-valves; and it consists in a novel construction of valve whereby it is balanced and not liable to get leaky and out of order by wear and long use; and it also consists in an improved method of operating the same, as hereinafter set forth, reference being had to the accompanying drawing, forming part of this specification, in which—

Figure 1 is a vertical section of my improved governor and stop-valve. Fig. 2 is a top view of the same. Figs. 3 and 4 are detail views.

Similar letters of reference in the different figures indicate corresponding parts.

The pipes *A a* are connected together by a globe, *C C*, Fig. 1, the ends of the pipes being slightly separated by an opening, *s s*, as shown.

A valve, *I*, is attached to the stem *p* and slides vertically in the pipe *a*. This valve *I* is open through its center, as shown by *i i i* in top view, Fig. 4, of valve *I*, and by *i*, Fig. 1, so that steam may pass into *a* in the rear of the valve *I* and give an equal pressure of steam above and below valve *I*. The valve *I* is substantially a section of pipe which, by being depressed or elevated in the pipe *a*, elongates or shortens the pipe *a* at its lower end, so as to enlarge or diminish the size of the aperture *s s* between the adjacent ends of the pipes *A A*.

To make the valve *I* quite tight when closed against *A* it is provided with metallic packing-rings *j j*, Fig. 1, similar in construction to those used on engine-pistons, the said packing-ring being self-adjusting for taking up wear by means of springs *r r r*, Fig. 4.

The top of pipe *a* is covered with a plate or head, *d*, which has two uprights *e e*, Fig. 3, and these uprights support a cross-head, *F*, in a fixed manner, and the cross-head is provided at its center with double cams or inclined planes, *f f*, upon its upper and lower sides.

The valve-stem *p* has a double cam or inclined plane *H h*, fixed thereto below the cross-head *F*, which engages with the inclined planes on the lower side of the cross-head, and the valve-stem *p* has also a double cam, *K k k*, fixed to it above the cross-head *F*, which engages with the cams or inclined planes *f f* upon the upper side of the cross-head *F*.

L, Figs. 1 and 2, is a lever which is fitted on the upper end of the valve-stem *p*, and has a handle at *L*, and at its opposite end it connects with the governor-rod *n*, Fig. 2, by a detachable connection, *M*, Figs. 1 and 2. This connection *M* is formed by a lever, *m*, which is pivoted to the governor-rod *n* at *u*, Fig. 2, so that the short end of lever *m*, in connection with rod *n*, forms a pair of jaws for seizing the bolt *v* on the valve-stem lever *L*, the said jaws being held closed upon bolt *v* by a spring, *t*, and are disengaged from the bolt *v* by pressing the handle *m* in against *n*, so that the jaws *M*, Fig. 2, are thrown open. The bolt *v* is adjustable on the lever *L*, so that the throw of the valve *I* and governor-rod *n* may be changed with relation to each other, the bolt *v* sliding out and in on the lever *L*, and is secured in place by a set-screw.

Its operation is as follows: The fluctuations or oscillations of the governor-rod *n* give a rotary movement to the valve-stem *p* by means of the lever *L*, and as the valve-stem is turned in one direction by an increase in the speed of the engine, then the cams *h h*, Fig. 1, acting upon the lower fixed cams, press the valve-stem *p* and valve *I* downward, so as to diminish the size of the delivering-aperture *s s*; and when the governor-rod *n* is moved in the opposite direction by a slackening in the speed of the engine, then the upper valve-stem cams *k k* act upon the fixed cams *f f* on the upper side of the cross-head *F* and elevate the valve *I*, so as to supply more steam to the engine, and thereby regulate the velocity of the same.

This valve can be readily used as a stop-valve by throwing off the governor-rod *n* and turning the valve *I* down by means of the hand-lever *L*, Figs. 1 and 2.

It will be seen that the pressure of steam on the valve *I* is balanced on all sides, so that the steam-pressure can at no time affect or obstruct the action or working of the valve.

By this means I obtain a very sensitive and

durable governor-valve, and which is also available as a stop-valve.

Having thus described my invention, what I claim as new, and desire to secure by Letters Patent, is—

1. The divided pipe A *a*, globe C, and pipe B, tubular valve I *j* *j*, and stem *p*, arranged and operating substantially as herein shown and described.

2. The valve-stem *p*, with cams *h* *h* *k* *k*, the fixed cams *f* *f*, stop-lever L, and detachable governor-rod *n*, arranged and operating as and for the purpose set forth.

JOHN CRAWLEY.
